UNITED STATES PATENT OFFICE.

LEONIDAS G. WOOLLEY, OF GRAND RAPIDS, MICHIGAN.

VAPORIZER FOR GAS-ENGINES.

SPECIFICATION forming part of Letters Patent No. 450,091, dated April 7, 1891.

Application filed September 26, 1890. Serial No. 366,274. (No model.)

To all whom it may concern:

Be it known that I, LEONIDAS G. WOOLLEY, a citizen of the United States, residing at Grand Rapids, in the county of Kent and State of Michigan, have invented certain new and useful Improvements in Vaporizers for Gas-Engines; and I do hereby declare the following to be a full, clear, and exact description of the invention, such as will enable others skilled in the art to which it appertains to make and use the same.

My invention relates to a vaporizer for gas-engines. The object of my invention is to provide a simple apparatus for vaporizing gasoline or other volatile liquids for use as an explosive agent in gas-engines; and it consists in the combination, with a gas-engine, of a vaporizer of novel construction, substantially as hereinafter fully described and as set forth in the claims, reference being had to the accompanying drawings, wherein—

A represents the cylinder, and B the compressed-air tank, of an ordinary gas-engine. Between the cylinder and the air-tank is arranged the vaporizer D, which is filled with sponge or other suitable porous absorbent material H, and connected to the cylinder and tank, respectively, by suitable vertical pipes K K', the latter having the throttle-valve G for admitting air from the tank. Mounted above the vaporizer D is a full reservoir C, having a plug M for feeding the same and communicating with the vaporizer by a suitable coupling provided with a needle-valve E and a sight-feed F. At the upper end of the pipe K is a chamber N, which has a plug O, and is also filled with sponge or other suitable material H', and which chamber has a perforated diaphragm Q over the port R into the valve leading to the cylinder A, which valve has a rod P connected to it and by which it is operated from the moving parts of the engine, and at the bottom of the port R is a drip-cup I'. An air-pipe L connects the top of rod K and reservoir C to equalize the pressure above and below in C.

I is a drip-cup or vessel below K to receive any unvaporized liquid that may pass through the vaporizer D.

J and J are glass gages to show the state of the contents of the vessels C and I.

Compressed air from the chamber B being admitted to the vaporizer D through the valve G, takes up the vapor from the liquid in the sponge, forming an explosive compound which passes through the vertical pipe K and its connections into the upper end of the cylinder A, and is then fired, any excess of liquid overflowing into the drip vessels I and I'. The vaporizer is arranged below the combustion-chamber of the cylinder and connected thereto by a vertical pipe, whereby danger of a flow of the liquid into the chamber by gravity is obviated.

What I claim is—

1. The combination, with a gas or vapor engine, of a vaporizer consisting of an inclosed chamber filled with sponge or other suitable porous material and connected, respectively, with the compressed-air chamber and the cylinder of the engine, a drip-cup between the vaporizing-chamber and the cylinder of the engine, and a fuel-reservoir mounted above, supported on, and connected with the vaporizing-chamber, substantially as set forth.

2. The combination, with a vapor or gas engine, of a vaporizer consisting of an inclosed chamber filled with sponge or other suitable porous material and connected, respectively, with the air-chamber and the cylinder of the engine, a drip-cup between the vaporizing-chamber and the cylinder of the engine, a fuel-reservoir connected with the vaporizing-chamber, and an air-pipe L, connecting the pipe K with the fuel-reservoir, substantially as and for the purposes set forth.

3. The combination, with a gas or vapor engine, of a vaporizer consisting of an inclosed chamber D, filled with sponge or other suitable material and connected, respectively, with the compressed-air chamber and the cylinder of the engine, a second chamber N, filled with sponge or other suitable material between said chamber D and the cylinder, connections between chambers N and D and said cylinder, a drip-cup between said chambers N and D, and a fuel-reservoir connected to the chamber D, substantially as set forth.

4. A vaporizer for vaporizing volatile liquids, composed of a vaporizing-chamber D, filled with sponge or other suitable material,

a fuel-reservoir C, mounted on the chamber D and communicating therewith, a supplementary vaporizing-chamber N, also filled with sponge or other suitable material, a drip-
5 cup connected to the chamber N, and a drip-cup I between chambers D and N, connections between said chambers and the air-chamber and the cylinder of the engine, a fuel-reservoir C, mounted on the vaporizing-chamber D, connected thereto, and an air-

pipe L, connecting the pipe K with said fuel-reservoir for equalizing the pressure in said reservoir, substantially as and for the purpose specified.

In testimony whereof I affix my signature in 15 presence of two witnesses.

LEONIDAS G. WOOLLEY.
